MACHINE FOR OPERATING UPON SHOES

Homer F. Smith, Chicago, Ill., assignor to United
Shoe Machinery Corporation, Flemington,
N. J., a corporation of New Jersey

Application March 24, 1942, Serial No. 436,017

18 Claims. (Cl. 12—67.2)

This invention relates to machines for operating upon shoes, and is herein illustrated as embodied in a machine for operating upon the inseam materials and welts of lasted shoes.

In the manufacture of welt shoes, after the upper has been lasted and the welt has been attached thereto, the materials of the inseam are usually trimmed close to the row of stitches connecting the welt, the upper and the channel flap, after which it is desirable to pound down the inseam materials and flatten out the welt prior to a sole attaching operation, in order that the sole will fit closely on the bottom of the lasted shoe. It is an object of the present invention to provide an improved machine of the type referred to, which will be especially adapted to facilitate the presentation of the work to the machine and to guide it past the operating instrumentalities, as well as being rapid and smooth in its operation.

To this end and as illustrated, the invention provides, in a machine of the type referred to, a rotatable beating tool, and a pair of members arranged to engage therebetween the welt of a lasted shoe to be operated upon to feed the shoe past the beating tool. Preferably and as shown, the members are rolls which operate to flatten the welt, and the beating tool is arranged to engage the inseam materials to beat them down as a shoe is advanced past the tool. Preferably, too, and as shown, one of the rolls is resiliently mounted for movement toward or away from the other, thereby to facilitate positioning of the work in the machine, and is so shaped as to enter the welt crease of a shoe for positioning and guiding the shoe relatively to the beating tool.

These and other features of the invention are disclosed in the following specification and in the accompanying drawings, and are pointed out in the claims.

In the drawings,

Fig. 1 is a view in side elevation of a beating machine constructed in accordance with the invention;

Fig. 2 is a vertical cross sectional view of the upper portion of the machine shown in Fig. 1;

Fig. 3 is a vertical cross sectional view of the upper portion of the machine showing certain of the operating instrumentalities on an enlarged scale;

Fig. 4 is an end view of a portion of the machine, showing the relation of the operating tool to the work;

Fig. 5 is an end view, partly in section, of the

beating tool in engagement with work positioned in the machine;

Fig. 6 is a side view, partly in section, illustrating the operation of a slashing knife forming part of the mechanism of the machine; and

Fig. 7 is a plan view of a portion of a lasted shoe after the welt has been slashed.

The invention is illustrated in connection with a machine for performing beating operations upon a shoe, such as a lasted shoe 10, Fig. 5, having a welt 12 and trimmed inseam materials 14. The operating instrumentalities comprise a combined feed roll and work support 16 and a combined feed and backing roll 18 arranged frictionally to engage opposite sides of the welt 12 for flattening the welt and for advancing the shoe past a rotary beating tool 19 arranged to pound down the inseam materials of the shoe.

The backing or feed roll 18 comprises a ring 20, Figs. 2 and 3, secured to an enlarged head 22 on a hollow shaft 24, positioned in a bearing 26 in an arm 28 of the machine frame 30. The roll is arranged for rotation about the axis of the shaft, and cooperates with the work support 16 to advance a shoe past the work support and the beating tool, and at the same time exerting pressure upon the welt to flatten it.

The work support 16 is in the form of a conical roll, Figs. 2 and 4, the outer surface 29 of which extends tangentially of the outer surface of the roll 18. The work support is beveled as shown at 31 to facilitate the engagement of the roll in the welt crease of a shoe in positioning the shoe relatively to the tool 19 and in guiding the shoe past the tool. The work support 16 is pivoted upon a bracket 32, mounted for vertical movement in a collar 34 and held against rotation by a key 35. The bracket is normally urged upwardly toward the roll 18 by a stiff spring 36 located within the collar, and having its lower end bearing upon a bushing 38 threaded into the collar. The pressure of the spring is readily adjusted by rotating the bushing 38 in the collar 34, the bushing being secured in adjusted position by a lock nut 39.

The work support 16 is rotated by means of a shaft 40 extending through a sleeve 41 carried by the bushing 38 and positioned centrally of the collar 34, the shaft having at its upper end a gear 42 in mesh with a pinion 44, carried by the bracket 32 and which, in turn, is in mesh with a gear 46 mounted upon a stud 48 and meshing with teeth 50 on the work support. The shaft 40 has at its lower end splines 52 slidably

connecting the shaft with a gear 53 which meshes with a pinion 54, mounted upon a horizontal shaft 56 and is arranged to be rotated by means of a sprocket 58 engaging splines 59 on shaft 56 and driven by a chain 60.

In order to provide for adjustment of the work support 16 laterally of the feed roll 18, to support welts of various widths, the sleeve 34 is mounted upon a base 62 having a dovetailed portion 64, resting upon a horizontal projection 66 on the machine frame. The base with the sleeve and work support can be adjusted laterally of the feed roll by means of a screw 68, carried by the projection 66 and making threaded engagement with the lower portion of the base.

To provide for depressing the work support 16, to permit the insertion between the support and the feed roll 18 of the welt of a shoe to be operated upon, there is provided a treadle 70 connected by rods 72 and 73 to the lower end of the shaft 40, so arranged that upon depression of the treadle the work support will be lowered against the resistance exerted by the spring 36.

The beating tool 19 comprises a hub 74, Figs. 2, 3 and 4, formed upon one end of a shaft 75, and having four guideways 76 spaced 90° apart and in which are positioned beating members 78 having curved work engaging surfaces 80 which are generally circular in cross section, but are slightly relieved in the direction of rotation of the tool which, as shown in Fig. 4, is in a clockwise direction. The beating members are provided with slots 82 extending diagonally across the axes of the members, each slot having positioned therein a pin 84 carried by a plate 86 secured by a bolt 88 to the shaft 75. In order simultaneously to adjust the beating members outwardly of the axis of the shaft, the bolt 88 is loosened and the plate is turned, thereby causing the pins 84 to force the beating members inwardly or outwardly, depending upon the direction of rotation of the plate. After the members have been adjusted, the bolt 88 is tightened, and the members are held in their adjusted position by bolts 90 extending through elongated slots 92 in the members and into the hub. The outer end of the shaft 75 is supported by ball bearings 94 positioned within the head 22 of the shaft 24, the other end of the shaft 75 being supported in a ball bearing 96 supported upon the frame 30.

Various parts of the machine are driven from a pulley 98 through a belt 100 which passes over an idler 101 and over a pulley 102 on a shaft 104 which carries a pinion 106 meshing with a gear 108. The last-mentioned gear has secured thereto a pinion 110 in mesh with a gear 112 secured to the sleeve 24 for rotating the feed roll 18. The gear 112 carries a sprocket 114, which drives the chain 60 to effect rotation of the work support 16. The gears are so selected that the pressure roll 18 and work support 16 are driven at substantially the same surface speed, the rotation of the pressure roll being approximately 60 R. P. M. The beating tool 19 is driven by a separate belt 116, which passes over an idler 117 and over a driving pulley 118 to effect rotation of the shaft 75 at a rate of about 2500 R. P. M.

When the welt is attached to the shoe upper, portions of the welt passing around the toe portion of the shoe are usually puckered, due to the sharp curve along which the welt is bent. Consequently, in order to cause the welt to lie flat, it is customary to slash it along the toe, after which it can be more readily flattened out. Accordingly, there is provided a slashing knife 120, which can be operated under manual control to

produce slashes in the toe portions of the welt, such as slashes 122 in Fig. 7. Preferably, the knife has a thin tapered end portion 124. The knife is arranged to slide along a bracket 126 positioned adjacent to and slightly above the work table 16, and is carried by a lever 128 pivoted thereto at one end, and having upon its other end a stud 130. This stud is positioned in a groove 132 in an oscillating member 134, pivoted on the frame and connected to an arm 136 mounted upon an eccentric 138. Connected to the lever 128 is a link 140 pivoted upon a bell crank lever 142 arranged to be actuated by a rod 144 operatively connected to a treadle 146 (Fig. 1) by a system of pivoted links 148, 150 and 152, and a rod 154. The eccentric 138 is arranged to be continuously rotated by means of a belt 156 driven by the pulley 118. When the parts are in the positions shown in Fig. 3 in which the stud 130 is at the axis of the pivot of the member 134, movement of the arm 136 under action of the eccentric causes the member 134 to be oscillated about the stud 130 without producing any movement of the knife. However, upon depression of the treadle 146, the roll is shifted along the groove 132 into a position such that the eccentric will impart a reciprocating movement to the knife to produce one or more slashes 122. The length of the stroke of the slashing knife 120 is controlled by the amount which the stud 130 is shifted along the groove 132 in the oscillating member 134, which, in turn, is proportional to the distance the rod 144 is depressed. In order to restrict the stroke of the knife to a predetermined length, there is provided a screw stop 158 (Fig. 1) adapted to be engaged by an abutment 160 on the link 150 when the treadle 146 is depressed, thereby limiting downward movement of the rod 144 and consequently limiting the movement of the stud 130 to control the length of stroke of the slashing knife.

In the operation of the mechanism above described, the treadle 70 is depressed to lower the work supporting roll 16. The shoe to be operated upon is then positioned with the welt thereof resting upon the work support 16, with the beveled portion of the support extending into the welt crease of the shoe, after which the treadle is released, and the spring 36 forces the work support with the work in position thereon up against the pressure feed roll 18. Upon rotation of the rolls 16 and 18, the shoe is moved between the rolls past the beating tool 19, the operator exerting a light pressure upon the shoe to maintain it in contact with the work support 16. During the operation, the pressure exerted by the rolls is effective to flatten out the welt of the shoe, and the beating members 78 of the beating tool 19 are effective to pound down the inseam materials of the shoe. As the shoe is advanced past the rolls and the toe portion thereof is reached, the operator may depress the treadle 146 to cause the slashing knife 120 to produce one or more slashes in the toe portion of the welt. The construction and arrangement of the parts above described thus provides mechanism by which a shoe can be readily presented to operating instrumentalities and advanced automatically past such instrumentalities at a substantially uniform speed, which ensures uniform operation of the instrumentalities upon the work.

Having described my invention, what I claim as new and desire to secure by Letters Patent of the United States is:

1. A machine for operating upon shoes comprising a pressure roll, a work supporting roll adjacent to the pressure roll, means mounting the work supporting roll for movement toward and away from the pressure roll and for movement laterally thereof, a beating member adjacent to the pressure roll, and means for driving the rolls in a direction to advance a shoe to be operated upon past the beating roll.

2. A machine for operating upon shoes comprising a work support, a pressure roll located adjacent to the work support, resilient means normally operable to force the work support toward the pressure roll for gripping between them the welt of a shoe to be operated upon, a beating tool located adjacent to the pressure roll, and means for rotating the pressure roll and the work support in a direction to advance a shoe past the beating tool.

3. A machine for operating upon shoes comprising a rotary toothed tool for beating down the inseam materials of a shoe, two rolls for engaging the welt of the shoe to be operated upon, and means for rotating the rolls to advance the shoe past the beating tool.

4. A machine for operating upon shoes comprising two pressure rolls adapted to engage opposite sides of the welt of a lasted shoe to be operated upon, a beating tool located adjacent to the rolls, and means for rotating the rolls in a direction to advance the shoe past the beating tool.

5. A machine for operating upon shoes comprising a rotary beating tool, a pair of rolls located adjacent to the beating tool and constructed and arranged to engage opposite sides of a welt of a shoe to be operated upon, resilient means for forcing the rolls toward each other to grip the welt between them, and means for rotating the rolls to advance the shoe past the beating tool, thereby to flatten out the welt and beat down the inseam materials of the shoe.

6. A machine for operating upon shoes comprising a beating tool, a conical work support adapted to enter the welt crease of a shoe presented to the machine with the inseam materials of the shoe located in engagement with the beating tool, a pressure roll cooperable with the work support to frictionally engage the welt of the shoe, and means for rotating the rolls in the direction to advance the shoe past the beating tool.

7. A machine for operating upon shoes comprising a rotary beating tool, a pressure roll and a conical work support located adjacent to the beating tool, the pressure roll and the work support being in alinement for the purpose of engaging opposite sides of a welt of a shoe to be operated upon, means for rotating the pressure roll and the work support in a direction to advance the shoe past the beating tool, and means for operating the beating tool independently of the pressure roll and the work support.

8. A machine for operating upon shoes comprising a conical work support adapted to enter the welt crease of a lasted shoe, a pressure roll located adjacent to the work support, means for forcing the pressure roll and the work support toward each other to grip between them the welt of the shoe presented to the machine, a beating tool located adjacent to the pressure roll, and means for rotating the pressure roll and the work support in a direction to advance the shoe past the beating tool.

9. A machine for operating upon shoes comprising a rotary beating tool, a pair of rolls located adjacent to the beating tool, one of said rolls having a conical portion adapted to enter the welt crease of the shoe to guide the shoe, and means for rotating the rolls in a direction to advance the shoe past the beating tool.

10. A machine for operating upon shoes comprising a rotary beating tool, a pair of rolls located adjacent to the beating tool, one of said rolls having a conical portion adapted to enter the welt crease of a shoe to guide the shoe, means for rotating the rolls in a direction to advance the shoe past the beating tool, and means for moving the rolls relatively to each other to provide for the location of the welt of the shoe between the rolls.

11. A machine for operating upon shoes comprising a beating tool, a pair of rolls located adjacent to the beating tool, one of the rolls having a conical portion adapted to enter the welt crease of a shoe for guiding the shoe, means for rotating the rolls in a direction to advance a shoe past the beating tool, means for moving the rolls relatively to each other to provide for the location of the welt of the shoe between the rolls, and means mounting the conical roll for movement laterally of the beating tool for locating the shoe in predetermined operative relation relatively to the tool.

12. A machine for operating upon shoes comprising a beating tool, a pair of rolls located adjacent to the beating tool, one of the rolls having a conical portion adapted to enter the welt crease of a shoe for guiding the shoe, means for rotating the rolls in a direction to advance a shoe past the beating tool, means for moving the rolls relatively to each other to provide for the location of the welt of the shoe between the rolls, means mounting the conical roll for movement laterally of the beating tool for locating the shoe in predetermined operative relation relatively to the tool, and means for rotating the beating tool at a high speed relatively to the speed of the rolls.

13. A machine for operating upon shoes comprising a rotary beating tool, a pair of rolls located adjacent to the beating tool, one of said rolls having a conical portion adapted to engage the welt crease of a shoe to guide the shoe, means for rotating the rolls in a direction to advance the shoe past the beating tool, means for moving the rolls relatively to each other to provide for the location of the welt of the shoe between the rolls, and means for shifting the position of one of the rolls relatively to the other for locating the shoe in operative position with trimmed inseam materials in alinement with the beating tool.

14. In a machine for operating upon shoes, a beating tool comprising a plurality of arms, each of which terminates in a curved beating member, a pair of rolls adjacent to the beating tool, one of said rolls having a portion constructed and arranged to engage the welt crease of a shoe to be operated upon to locate the shoe in predetermined position relatively to the beating members, and means for rotating the rolls in a direction to advance the shoe past the tool.

15. In a machine for operating upon shoes, a hollow shaft, a pressure roll carried upon the shaft at one end thereof, a second shaft extending through the hollow shaft and having a beating member located on one end thereof adjacent to the pressure roll, a work supporting

roll adjacent to the pressure roll, means for driving the pressure roll and the work supporting roll at substantially the same speed, and means for driving the beating tool at a comparatively high speed relatively to the rolls.

16. In a machine for operating upon shoes, a beating tool comprising a hub having a plurality of radially extending grooves formed therein, a plurality of beating members located in the grooves, each of the beating members having a slot inclined relatively to the groove in which it is positioned, and a plate carried by the hub and having a plurality of pins extending into the grooves in the members, whereby upon rotation of the plate the members are adjusted simultaneously along the grooves.

17. A machine for operating upon shoes comprising a beating tool, two feed rolls constructed and arranged to engage opposite sides of the welt of a shoe presented to the machine, means for driving the rolls in a direction to advance the shoe past the beating tool, a welt slashing knife

located adjacent to the rolls, and means for reciprocating the slashing knife comprising an arm arranged to be continuously oscillated about a fixed axis, a link having its inner end pivoted to the knife and its outer end slidably connected to the arm, and means for shifting the position of the outer end of the link relatively to the arm for varying the stroke of the knife.

18. A machine for operating upon shoes comprising a beating tool, means adapted to engage the welt of a shoe to be operated upon for feeding the shoe past the beating tool, a welt slashing knife located adjacent to the feeding means, and means for reciprocating the knife comprising an arm arranged to be oscillated about a fixed axis, a link having its inner end pivoted to the knife and its outer end slidably connected to the arm, and manually operated means for shifting the position of the outer end of the link along the arm for varying the length of stroke of the knife.

HOMER F. SMITH.
